UNITED STATES PATENT OFFICE.

GLENN H. CURTISS, OF BUFFALO, NEW YORK, ASSIGNOR TO CURTISS AEROPLANE AND MOTOR CORPORATION, A CORPORATION OF NEW YORK.

RECONNOITERING-AEROPLANE.

1,323,842.

Specification of Letters Patent.

Patented Dec. 2, 1919.

Application filed March 31, 1916. Serial No. 88,088.

To all whom it may concern:

Be it known that I, GLENN H. CURTISS, a citizen of the United States, residing at Buffalo, in the county of Erie and State of New York, have invented certain new and useful Improvements in Reconnoitering-Aeroplanes, of which the following is a specification.

My invention relates to heavier-than-air flying machines and more particularly to aeroplanes of the high speed reconnoitering type.

It is essential for high speed work that the machine be well balanced, freed, in so far as practicable, from head resistant surfaces or formations, and effectually streamlined throughout. The second and last essentials make directly for increase in rate of travel while the first essential indirectly produces the same result in that the machine is more responsive to its various controls and its directional changes are obtained with greater efficiency and with a relatively increased speed. My invention is possessed of these speed characteristics to a marked degree and yet its structural form is such that the body supporting planes possess the highest or at least the requisite strength. Such characteristics are of the utmost importance in military aeroplanes designed primarily for scout duty since it is incumbent upon the scout machine to outdistance an armed enemy aircraft in the event of aerial attack.

To secure high speed without an increase in propelling power, I propose to materially cut down the number of struts and braces; eliminate altogether the heretofore numerous wires, turnbuckles, etc.; and streamline the fuselage and each and every part of the machine extended therewithout. Such an improved and simplified arrangement of parts is not only possible but entirely practical when it is considered that a means is provided whereby the structural strength and rigidity of the machine is in no way reduced. A craft built according to my invention will travel at the very maximum possible speed and with the highest factor of safety attainable in the existing state of the aeronautical art.

Many additional structural advantages conducive to the object sought will be more explicitly pointed out hereinafter.

In describing my invention in detail, ref-

erence will be had to the accompanying drawings wherein like characters of reference designate like or corresponding parts throughout the several views, of which;

Figure 1 is a side elevation of my improved scout machine;

Fig. 2 is a front elevation;

Fig. 3 is a top plan view;

Fig. 4 is a detail perspective view of the interwing struts and braces;

Fig. 5 is an enlarged detail sectional view illustrating the manner in which the tension wires are made fast at one end to the wing beam;

Fig. 6 is a detail side elevation of the empennage of the craft;

Fig. 7 is a top plan view of the empennage;

Fig. 8 is a detail elevation, partly in section and partly broken away, of one of the landing gear wheels and that portion of the landing gear directly engaging with the landing gear axle;

Fig. 9 is a transverse sectional, view partly in elevation, of that portion of the landing gear illustrated in Fig. 8;

Fig. 10 is a detail cross sectional view of one of the compression struts, and

Fig. 11 is a detail section of the stern post illustrating the opening therein through which the elevator control mechanism extends, and

Fig. 12 is a front elevation of a modification.

In the embodiment of my invention herein illustrated and by me considered preferred, the numerals 10 and 11 designate respectively the upper plane and the lower plane of a biplane of the tractor type. The propeller denoted 12 is mounted at the forward end of the fuselage or body 13 of the craft and is equipped at its hub portion with a substantially frusto-conical hood or nose-piece 14 of a size in circumference approximating the circumference of the nose end of the fuselage to constitute in reality a forward prolongation thereof.

Immediately aft of the propeller 12 and almost entirely inclosed in the forward end of the fuselage 13 is the propelling power plant 15 for the craft. While I have illustrated the machine as equipped with a motor having its cylinders arranged in angularly inclined banks to extend without the fuselage at opposite sides of the longitudinal axis,

of the machine, it is to be understood that such an engine is only preferred and forms no part of the invention hereinafter claimed. Such portion or portions of the engine as 5 extend without the fuselage are streamlined in so far as practicable through the medium of hoods 16 arranged, one over each bank of projecting cylinders.

It will be observed upon reference to Fig. 10 1 of the drawings that the fuselage or body of the craft is effectually streamlined from end to end and tapered at its forward end to constitute a streamline nose. Intermediate the propeller and the propelling power 15 plant 15, I locate the radiator 17 for the engine. In size and configuration, the radiator continues the streamline of the fuselage forwardly to a point in such proximity to the nose piece 14 as to receive the full effect 20 of a continuous blast of air directed rearwardly from the propeller 12. Mounted on the propeller shaft and inclosed by the nose-piece 14 is a fan 18 of a size and construction to effectually cool the radiator 17 by 25 the air blast created thereby. The fan 18 acts in conjunction with the propeller 12 in imparting to the radiator 17 a maximum cooling effect.

By locating the propelling power plant 30 15 forwardly of the center of pressure and disposing the pilot's cockpit 19 aft of the center of pressure, it is evident that the weight of the pilot will materially counter-balance and offset an otherwise unbalanced 35 structure. To minimize the head resistance in the vicinity of the cockpit, a windshield 20 of streamlined form (preferably celluloid) is disposed in such relation to the cockpit as to protect that portion of the pilot 40 (the head and face) necessarily extended without the fuselage. The fuselage immediately aft of the cockpit 19 is vertically enlarged or extended as indicated at 21 to afford a streamlined prolongation of or 45 rather to be in line with that portion of the pilot extended above the coaming of the cockpit. The seat for the pilot is designated 22 and indicated in dotted lines in Fig. 1.

50 To further reduce the head resistance incident to flight, the number of struts and braces is reduced to a minimum and substantially all lift and drift wires and such like elements eliminated. The planes or 55 supporting surfaces 10 and 11 are braced from end to end via the landing gear, designated as an entirety by the numeral 23, of the machine. The landing gear in the embodiment here shown comprises a landing 60 gear axle 24, hollow throughout; cross-arranged, downwardly diverging forward chassis-struts 25 and diverging aft chassis-struts 26. The forward chassis-struts 25 are streamlined and extend forwardly at a 65 slight angle to the vertical into the interior

of the body of the machine that the landing gear axle 24 may be accordingly braced. The struts 25 at one end engage with the axle 24 adjacent the terminals thereof and at their opposite end with the engine bed 70 or support designated 27. The entire weight of the propelling power plant is thus imposed directly on the axle 24 at such points as are capable of receiving the greatest compression strains. As hereinbefore pointed 75 out, the struts 25 cross interiorly of the fuselage and engage with the engine bed after the fashion indicated by the dotted lines in Fig. 2. This cross arrangement is 80 conducive to greater strength and rigidity. 85 They may be joined at their point of crossing or intersection.

Landing gear wheels of a special construction and design, (to be hereinafter fully disclosed) are mounted, one at each end of 85 the landing gear axle 24. The wheels are designated each as an entirety by the numeral 28. Compression struts 29 and 30 engage with the terminals of the axle 24 and extend diagonally to the lower support- 90 plane 11 to which they are connected by any suitable means. As illustrated to advantage in Figs. 4 and 8, the mentioned struts 29 and 30 lie substantially contiguous throughout their entire length and thus 95 brace the lower plane or wing at a point in the approximate vertical plane of the center of pressure of the machine. In reality the compression struts 29 and 30 constitute but a single strut in that the two 100 are streamlined as a unit and as indicated at 31 and 32, the filling whereby the streamline construction is obtained being inclosed and covered with a suitable fabric 33. The struts 29 and 30 are preferably hollow 105 throughout. The strut construction just described is duplicated at each side of the machine as before suggested that the strains on the lower wing may be transmitted to the terminals of the landing gear axle 24. 110 Bolts 34 mounted at the terminals of the said axle to pass transversely therethrough and through the contiguous struts 29 and 30 serve to releaseably fasten the struts to the landing gear of the machine. The spread 115 of the upper wing is materially greater than the spread of the lower wing. The upper wing 10, like the lower wing 11, is braced to the landing gear of the machine and from end to end via the landing gear axle 24. 120 But two wing posts, each designated as an entirety by the numeral 35 interconnect the wings, each post engaging the lower wing 11 in the vertical plane of the compression struts 29 and 30 and consequently approxi- 125 mately in the vertical plane of the center of pressure on said lower wing. The wing posts, collectively speaking, extend in diverging relation and in alinement with the compression struts 29 and 30 to engage with 130

the upper wing at points suitably removed from the ends of the wing. Each wing post comprises a pair of compression struts 36 and 37, hollow throughout. These struts 5 extend contiguously throughout the greater portion of their length but diverge at one end to consequently engage the upper wing 10 at points respectively fore and aft of the center of pressure of said wing. A web 38 10 connects the diverged struts 36 and 37 and constitutes what I shall hereinafter designate an anti-skid plane. The anti-skid planes are located at opposite sides of the longitudinal axis of the machine and in 15 such relation to the wing 10 as to jointly function with ailerons 38' to maintain lateral equilibrium during flight. Intermediate its ends, the upper plane 10 is braced to the interior of the fuselage by an 20 inverted V arrangement of struts 39 located respectively fore and aft of the center of pressure of said wing. The forward V arranged struts 39 engage with the engine bed or support.

25 Since the struts 29, 30, 36 and 37 function to take up the compression strains, and to a certain extent the tension strains, it is essential that a means be provided to take up the tension strains should the struts for 30 any reason work loose. To attain this end, both planes 10 and 11 are tied from end to end via the landing gear axle 24 through the medium of tie wires 40 and 41 which parallel the struts 29, 30, 36 and 37. The tie wires 35 act independently one of the other and extend in the manner stated from the upper wing 10, adjacent the outer ends thereof, to and through both the lower wing 11 and the landing gear axle 24. A continuity of 40 tying is thus in evidence and both planes are effectually braced in a manner offering a minimum of head resistance or drag. The tie wires, as illustrated in Figs. 4 and 10, lie without the struts 29, 30, 36 and 37 and 45 pass through the hollow landing gear axle 24. Both tie wires are inclosed however by fairing 31 and 32 for the compression struts 29 and 30 and the fairing (a duplicate of that just described) utilized to streamline 50 the wing posts 35 or the struts 36 and 37 which constitute the mentioned posts. The cross arranged forward chassis-struts 25 preclude distortion of the landing gear axle 24 since the mentioned struts brace the axle at 55 the terminals thereof or at the points where the greatest strains are imposed thereon. The landing gear axle like the other exposed parts of the machine is streamlined throughout its length.

60 While any type of fastening means may be utilized to secure the tie wires 40 and 41 to the upper wing 10, I preferably employ a fastening means such as that illustrated in Fig. 5. Said fastening means comprises 65 an interiorly threaded and adjustable eye-

section 42, and a complemental engaging and fastening screw 43, the latter penetrating a fitting 44 (preferably metallic) located and fastened as indicated at 45 against the upper side of the wing beam of the wing. 70 The tie wire is fastened to the eye-section 42 and drawn taut by adjustment of the screws 43.

To preclude the formation of air pockets at the various joints, the wing panels constituting the lower wing 11 are curved or rounded as indicated at 46 at the points where the said panels engage with the fuselage or body of the craft or else the curved section 46 may be built into the side of the 75 fuselage. The several struts, as indicated at 47 are also constructed in rounded form at the points where the several struts engage with the wings.

The empennage of the craft comprises the 80 usual vertical stabilizer 48, horizontal stabilizer 49, rudder 50 and elevator 51, each of which is symmetrically arranged as regards the streamline form and as illustrated to advantage in Figs. 6 and 7. To further 85 decrease the head resistance, the control means for the rudder 50 is located wholly 90 interiorly of the fuselage of the craft as is the control means for the elevator 51. The control means for the elevator 51 comprises 95 a shaft 52, a sprocket 53, a chain 54, a sprocket 55, and an elevator rod 56. By movement of the shaft 52 through any suitable 100 interiorly located control means, motion is imparted to the rod 56 through the 105 sprockets 53 and 55 and the chain 54. The chain 54 penetrates or operates within an opening 57 formed in the stern-post 58 of the machine. If desired, the sprocket 55 and the chain 54 may be located at one side 110 of the stern-post 58 to thus obviate the necessity of forming the opening 57 with the resulting weakening effect on the post. The rudder control means, not unlike the 115 elevator control means just described, comprises a pulley 59 mounted on the rudder post 60 over which pulley a suitable flexible control element 61 is operable that the rudder may be moved after the manner required. Such an arrangement will avoid 120 the use of king posts and other flight resisting elements now common to most machines.

Even the tail skid, designated 62, is 125 streamlined, and as illustrated in Fig. 6, inclosed in a collapsible covering 63 of a form in longitudinal cross section obviating the formation of vortices at the rear of the skid. Any suitable means, such as the spring indicated at 64, may be provided to normally maintain the skid extended with respect to the bottom of the tail end of the fuselage.

Coming now to a description of the landing gear wheels 28, it is observed that the 130

hub 65 of each wheel is of a size terminating at its opposite ends wholly within the confines of the wheel rim 66. Ordinarily a reduction in the size of the hub would tend 5 to weaken the wheel structure. To counteract this weakening tendency, the spokes of the wheels are arranged in pairs and disposed alternatively parallel as indicated at 67, and crossed as indicated at 68. The 10 spokes and hubs may be thus streamlined as a unit as indicated at 69 to secure a minimum of resistance and without extending the streamlining fabric or material laterally beyond the opposite faces of the rim. 15 While I have illustrated the embodiment of my invention which I consider preferred, I desire it to be understood that the arrangement of the struts may be varied as desired without in any way departing from 20 the spirit of the invention as claimed. It is of the utmost importance, however, that the number of exposed bracing and tying devices be cut to a minimum that the head resistance or drag may be proportionately 25 reduced. This reduction in the head resistance is positively essential to the reconnoitering or scout type of aeroplane which depends solely upon speed for its usefulness.

In the modification illustrated in Fig. 12 30 the cross-arranged axle braces are eliminated and instead direct braces used. The direct braces denoted 70 engage with the terminals of the landing gear axle and with the opposed longitudinals 71 which constitute the 35 engine bed. These braces when referred to in connection with the diagonal wing posts 72 and the intermediate inverted V arranged struts 73 constitute a substantially W-brace—i. e., a brace of well known structural rigidity.

What I claim is:

1. In an airplane, a fuselage, a landing gear mounted beneath the fuselage, superposed supporting surfaces, and combined 45 strut and wire connections between the supporting surfaces and the landing gear, the arrangement of the connecting elements being such that a substantial portion of both the lift load and the landing load of both 50 supporting surfaces is carried directly to the landing gear.

2. In an airplane, a fuselage, a landing gear mounted beneath the fuselage, superposed supporting surfaces, and combined 55 strut and wire connections between the supporting surfaces and the landing gear, the arrangement of the connecting elements being such that the greater portion of both the lift load and the landing load of both 60 supporting surfaces is carried directly to the landing gear.

3. In an airplane, a fuselage, a landing gear mounted beneath the fuselage, superposed supporting surfaces, combined strut 65 and wire connections between the uppermost

supporting surface and the landing gear located respectively at opposite sides of the fuselage, and fairing for the respective connections of a construction such that the struts and wires constituting the respective 70 connections are in each instance streamlined as a unit.

4. In an airplane, a fuselage, a landing gear mounted beneath the fuselage, a supporting surface, combined strut and wire 75 connections between the supporting surface and the landing gear located respectively at opposite sides of the fuselage, and fairing for the respective connections of a construction such that the struts and wires constituting the respective 80 connections are in each instance streamlined as a unit.

5. In an airplane, a fuselage, a landing gear mounted beneath the fuselage, superposed supporting surfaces, strut connections 85 between the lowermost supporting surface and the landing gear located respectively at opposite sides of the fuselage, the relation of struts to wings being such that the points of attachment of the struts to the 90 wings lie nearer the wing tips of the lower supporting surface than to the longitudinal vertical plane of the fore and aft axis of the craft, and wing posts continuing the struts beyond the lower supporting surface 95 in substantially angular alignment with them when viewed from either the front or rear, the points of attachment of the wing posts with the upper supporting surface being more distantly removed from the plane 100 of said axis than the points of attachment first mentioned.

6. In an aircraft, superposed supporting surfaces, a fuselage, a landing gear, and a substantially W-brace having the apex of its 105 intermediate legs extended into said fuselage from the landing gear and its outer legs extended diagonally outwardly and upwardly from said landing gear to the upper supporting surface.

7. In an aircraft, superposed supporting surfaces, a landing gear, a motor support mounted within the body of the craft, means bracing the upper supporting surface from beneath directly to said support, means directly bracing the landing-gear from above to said support, and wing posts spaced out laterally from the mentioned bracing means to interconnect and brace both supporting surfaces diagonally inwardly from 115 the ends of the upper supporting surface to and through the lower supporting surface for connection with said landing gear.

8. In an aircraft, supporting surfaces of unequal span, and diagonally extending 125 wing posts flared at one end to engage and effectually brace the larger supporting surface, that portion of each supporting surface extended out beyond said posts being of approximately equal length.

9. In an aircraft, superposed supporting surfaces, and struts contiguous throughout a portion of their length but diverging toward one end, each strut constituting a wing 55
 5 post interconnecting and bracing said supporting surfaces at an angle.
10. In an airplane, a fuselage, a landing gear comprising devices arranged symmetrically at opposite sides of the fore and aft 60
 10 axis of the craft, superposed supporting surfaces, and a substantially W-brace having its intermediate legs connecting with the fuselage and its outer legs extended outwardly and upwardly from said devices
 15 to and through the lower supporting surface for connection with the supporting surface next above.
11. In an airplane, a fuselage, a landing gear mounted beneath the fuselage, superposed supporting surfaces, a connection between the upper supporting surface and the fuselage, and a combined wing and landing gear truss comprising laterally separated V-braces having their apices founded upon 70
 20 the landing gear at points equi-distantly spaced laterally from the longitudinal vertical plane of the fore and aft axis of the craft, their inner legs extended into the fuselage, and their outer legs continuing beyond the lower supporting surface for connection with the upper supporting surface 75
 25 at points nearer the wing tips than the plane of said axis.
12. In an aircraft, a supporting surface, 80
 30 a landing gear, and separate compression means and tension means respectively inter-bracing and inter-tying said supporting surface and landing gear.
13. In an airplane, a fuselage, a landing gear mounted beneath the fuselage, superposed supporting surfaces, and upwardly diverging connections between the landing gear and the upper supporting surface, said 85
 40 connections being carried through the lower supporting surface at points nearer its tips than the longitudinal vertical plane of the fore and aft axis of the craft and attached to the upper supporting surface at points even more distantly removed from the plane 90
 45 of said axis.
14. In an aircraft, a supporting surface, a landing gear axle, means tying the sup- 95
 50
- porting surface from end to end by way of the landing gear axle, a body, and means directly bracing the terminals of the axle to said body. 55
15. In an aircraft, a supporting surface, a landing gear axle, means tying said surface from end to end by way of the landing gear axle, a body, and means cross bracing the axle to the interior of said body. 60
16. In an aircraft, superposed supporting surfaces, a landing gear axle, means tying the upper supporting surface from end to end by way of the lower supporting surface 65
 and said axle, a body, and struts interconnecting the axle and body to function with the tying means in the formation of a truss.
17. In an aircraft, superposed supporting surfaces, diagonal compression struts bracing the respective surfaces to the landing gear axle of the machine, means connecting the struts with said supporting surfaces, and means bracing the terminals of the landing gear axle to the interior of the body 70
 75 of the machine.
18. In an aircraft, superposed supporting surfaces, compression struts interconnecting and bracing the supporting surfaces to the landing gear of the machine, and common means tying the supporting surfaces from end to end by way of the struts and the landing gear. 80
19. In an airplane, superposed supporting surfaces, a wing strut extending from one 85
 85 to the other of the supporting surfaces, a brace wire extending from one to the other of the supporting surfaces, the wing strut and the brace wire being contiguous, a connection between one of the supporting surfaces and one end of the brace wire and a separate and independent connection between the same supporting surface and the corresponding end of the wing strut. 90
20. In an airplane, superposed supporting surfaces, a wing strut extending from one 95
 95 to the other of the supporting surfaces, said wing strut comprising upwardly diverging strut sections having a common connection with one supporting surface and separate connection with another supporting surface. 100

In testimony whereof I affix my signature.

GLENN H. CURTISS.
